UNITED STATES PATENT OFFICE.

WILLIAM DIETER, OF NEW YORK, N. Y.

INTERNAL-COMBUSTION ENGINE.

No. 842,182.

Specification of Letters Patent.

Patented Jan. 29, 1907.

Application filed April 17, 1905. Serial No. 255,910.

To all whom it may concern:

Be it known that I, WILLIAM DIETER, a citizen of the United States, residing at the borough of Brooklyn, in the city of New York, county of Kings, and State of New York, have invented certain new and useful Improvements in Internal-Combustion Engines, of which the following is a specification, reference being had therein to the accompanying drawings.

My invention relates to internal-combustion engines, and more particularly to the cylinder-head construction, the valve mechanism, and the parts appurtenant thereto.

15 The main object of the invention is to provide an internal-combustion engine wherein the various parts will be so constructed and arranged as to insure high efficiency and economy and to minimize the liability of the

20 jamming of or injury to the various valves and valve mechanisms or of injury to the cylinder-head resulting from a disarrangement or breakage of said valves or their mechanisms.

25 A further object is to provide automatic means cooling the bearings of the exhaust-valve stem.

30 A still further object is to provide simple means in an automatic exhaust-valve for initiating the opening thereof.

35 A still further object is to provide a cylinder-head construction wherein the breaking of a valve-stem will not cause material or irreparable injury to the cylinder-head casting; and a still further object is to provide a cylinder construction for internal-combustion engines which will be simple in design, which may be conveniently assembled, and which will be inexpensive to manufacture and economical to run.

40 The invention consists in the novel features of construction and combination of parts hereinafter set forth and described, and more particularly pointed out in the claims hereto appended.

45 Referring to the drawings, Figure 1 is a sectional elevation of one cylinder of an internal-combustion engine embodying my invention. Fig. 2 is a horizontal section of the cylinder-head and its appurtenances, taken on the line 2 2 of Fig. 1; and Fig. 3 is a cross-section of the cylinder-head and its appurtenances, taken on the line 3 3 of Fig. 1.

50 Like letters refer to like parts throughout the several views.

55 In the accompanying drawings, A indicates

the main cylinder-body, having radiating flanges common to air-cooled cylinders. Moving in this cylinder is the piston B, which is connected to the crank C by means of the 60 connecting-rod D and wrist-pin D'. The crank C is inclosed in an ordinary crank-shaft casing E, secured to the cylinder-body in any desired manner, but preferably by bolts E', arranged exteriorly of said body and serving 65 to connecting both the said casing and the head-casting F thereto. Inasmuch as the type of engine shown is a four-cycle, I provide therewith a link movement to be herein-after described actuated from the crank-shaft 70 through the gear G on said shaft and the gear G' on the counter-shaft H, the latter of which gears is of a diameter twice that of the former and carries a cam controlling said link movement.

75 This mechanism is such as is now commonly used, my invention relating more particularly to the cylinder-head and the valve construction and arrangement.

80 In the various types of internal-combustion engines now commonly in use the head-casting has therein two independent ports with puppet-valves controlling same. These ports and their valves are ordinarily in and carried by what may be termed a "bushing" 85 fitted in openings in the cylinder-head. In this construction the repeated contraction and expansion of the metals may shrink these bushings, thus causing leakage and weakness at those points. A further difficulty encountered is that inasmuch as one of these ports is exclusively for the exhaust and the other is exclusively for the intake the temperature of the cylinder-head about these ports is not uniform, and the only cooling about said exhaust 90 port and valve is effected through radiation from the cylinder-head resulting in continuous high temperature at this point—a difficulty which is further augmented by the inability to employ an exhaust-port of a capacity 95 to rapidly expand and exhaust the heated gases after each explosion. In this type of cylinder it is also found difficult to so operate the exhaust and the intake valves as to time accurately the initiation of the interval of exhaust and of charging. Another source of difficulty is that in case the valve-stem of either valve should break the broken part drops upon the piston and is liable to break out the entire cylinder-head or irreparably 100 damage it.

105 In my improved cylinder construction the

head-casting F is provided with a single enlarged port centrally thereof, which port is closed by a puppet-valve, (for convenience termed herein the "compression-valve,") the exhaust and the intake ports being arranged in connection with a chamber beyond said compression-valve, thus allowing a port of large capacity for both the exhaust and the intake and avoiding all bushings or seams incidental to the common construction above referred to, as well as avoiding within the cylinder a localization of the heat of the exhaust. This head preferably consists of a casting F, having a central supplemental chamber a therein, the said chamber having on opposite sides thereof an intake-port b and an exhaust-port c and in the bottom a cylinder-port d, establishing communication between said supplemental chamber and said cylinder. The exhaust-port c opens directly into an exhaust-chamber c', which discharges through the pipe c", preferably into a muffler. The port b opens into a vapor-chamber b', which is in communication through the pipe b" with a carburetor or other source of supply for gases or vapors.

On the under side of the casting F about the port d is formed a valve-seat for the compression-valve e of the puppet type.

In the top of the head-casting opposite to the cylinder-port d is an opening in which is snugly but removably fitted a flanged bearing f for the stem e' of the valve e, which bearing is elongated and projects into the chamber a in said casting. The bearing is held in place partly by the friction between it and the said casting and partly by the reaction of the spring e" acting between it and a collar e' on said stem e', which serves to normally close the valve e. The portion of the bearing beyond the casting F is formed into a suitable seat for said spring.

Carried on the counter-shaft H is a cam g, which is so set as to raise the link g' during two entire strokes of the engine. The upper end of this link is connected to one arm of a rocking lever g", the other arm of which is adapted to engage the valve-stem e' and open this valve e against the tension of the spring e". The lower end of the link g' is provided with an adjustable socket-sleeve g', which acts on a screw-thread on the lower end of the said link and is set by a lock-nut, as shown. A short rod g" is mounted in a bearing g' on the casing E with a face-plate thereon contacting with the cam g. The spring e" serves to hold said rod and said socket-sleeve in relation to each other, as well as to hold the face-plate of the former in engagement with the cam g.

Closing the intake-port b is a valve h, carried by a stem h', mounted in an elongated bearing i, projecting into the vapor-chamber b'. The outer end of this bearing is formed

expansion-spring h" of light tension acting against the collar h' on the outer end of the stem h' to normally close said valve. The face of the casting about the port b forms a valve-seat for said valve, which is situated within said supplemental chamber.

The port c is closed by a valve j, arranged within the exhaust-chamber c'. This valve has a bipart-stem j' j" mounted in the elongated bearing k, which projects into the said chamber. Fitted to the outer cup-like end of said bearing k is a cylindrical casing k', having a plurality of openings, as k", therein and a bearing in the end thereof for the outer end of the stem j". An expansion-spring l, also of small tension, is mounted on the stem j" and acting between the end of the casing k' and an enlarged collar j' serves to normally close the valve j, an annular stop j" serving to so limit the action of said spring as to permit a small independent action of the stem j" sufficient to insure a sudden start of the valve carried thereby free from the influence of the said spring. The collar j' is enlarged to serve as a plunger to expel and draw air into the casing k' to aid in cooling this valve mechanism.

The valve mechanisms herein described are entirely automatic, although, if desired, positively-operated valves may be employed in connection with other features of cylinder construction necessary to the employment of a compression-valve without departing from my invention, considered broadly.

The cylinder-head within the cylinder is dome-shaped, as shown in Figs. 1 and 3, thus providing walls inclined from the cylinder proper, A, to the port d, so that should the stem e' break and the valve e drop upon the piston the stem upon contact with the cylinder-head will be guided into the chamber, where contact with the bearing f will merely serve to displace said bearing without further injury to the head.

Carried by the cylinder-head F is a spark-plug m or other means of ignition.

In the drawings the several parts are in the position assumed just prior to the explosion of the charge then under compression by the spark-plug m. It will be observed that in this position the compression-valve e is closed, cutting out both the exhaust-valve j and the intake-valve h.

As the charge is fired the piston b is forced downward on its direct movement, turning the crank C and through the gears G G' the counter-shaft H, the latter making one revolution to two of the former. When the piston reaches the limit of its direct movement upon this the explosion or third stroke, the cam g, through the stem g", sleeve g', link g', and lever g", opens the valve e against the tension of the spring e" and holds it open during the next two strokes of the engine, thus establishing communication between

the cylinder A and the supplemental chamber *a* during this interval. With this opening of the valve *e* the products of combustion within the cylinder expand and are forced into the chamber *a* by the return reciprocation of the piston, the pressure within the chamber *a* being sufficient to overcome the tension of the spring *l* and automatically operate the exhaust-valve *j* to open the exhaust-port *c*. The slight play between the two parts of the valve-stem *j' j²* of said valve is sufficient to insure said valve being readily started.

Substantially simultaneously with the limit of the return reciprocation of said piston on the first stroke the spring *l* will automatically operate the valve *j* to close the port *c*.

The exhaust passes through the port *c* to the chamber *c'* and thence to the muffler or point of discharge through the pipe *c²*, the dimensions of these parts being sufficiently large to permit a further expansion of the heated exhaust and its rapid passage from the cylinder A and chamber *a*, and thus avoid excessive heating of the various parts thereby.

Upon the initiation of the first or charging stroke the valve *j* closes the port *c* and the port *d* remains open, thus causing the suction within the cylinder to automatically draw the valve *h* within the chamber *a* against the tension of the spring *h²*, opening the port *b* and permitting a charge of vapor or gas to be drawn from the carburetor or other source of supply into the cylinder A through the chamber *a*. Toward or upon the completion of the direct reciprocation of the piston upon the first stroke the valve *e* is operated by the spring *e²*, the cam *g* having assumed a position permitting the spring to so act to close the port *d*, it remaining closed during the next two strokes—the compression and the explosion. When the valve *e* is thus closed, the spring *h²* automatically closes the valve *b*.

It will be observed that the exhaust and the intake to the cylinder A are through the same port *d*, thus insuring substantial uniformity in the temperature within the cylinder—by "uniform temperature" not meaning that all parts of the cylinder are at the same temperature, but that adjacent to the cylinder-head the exhaust heats all parts of the cylinder under the same conditions and that therefore the incoming gases have a similar cooling effect on all these parts. Furthermore, as the exhaust in passing through the supplemental chamber *a* heats the bearing *f*, as well as the various valves and the walls of this chamber, the vapors as they enter this chamber prior to entering the main cylinder serve to cool these parts also. The vapors entering the cylinder also aid in cooling its walls, the heat absorbed serving also to increase the efficiency of the charge.

The cylinder may be further cooled by a water-jacket or the annular radiation rings or ribs, as shown in the drawings, the construction herein described being especially adapted for so-called "air-cooled" engines. 70

In the continued running of an engine the walls of the chamber *c'*, the bearing *k*, the chamber *k'*, the stem *j' j²*, and the spring *l* become heated. The extended surface afforded by the outside of the said chamber *c'* 75 results in the radiation of a large percentage of the heat units, the action of the plunger *j³* aiding in this cooling by maintaining a circulation of fresh air within the casing *k'* through the openings *k²* therein. The great clearance 80 afforded the exhaust also tends to limit the heating effect thereof.

It will be observed that by reason of the automatic action of the valves closing the exhaust and the intake port these valves are 85 controlled entirely by the piston, thus dispensing with the necessity for nicely-adjusted link mechanisms controlling these valves. Under some conditions, however, it may be desirable or preferred to use mechanically-90 actuated valves, and I do not wish to be understood as limiting the invention to an automatic valve mechanism.

If it be desired to limit the period of exhaust or of the intake to less than a full 95 stroke of the engine, it is apparent that the cut-out of the chamber *a* may be regulated as desired, through a variance in the contour of the cam *g*.

The economy in running the engine is due 100 to the increased efficiency of each charge by reason of the absorption by the vapors or gases of the heat from various parts within the chamber *a* and from the cylinder A and by reason of the possibility of running the 105 engine with the cylinder at a uniformly greater heat than is possible when the valve mechanisms are subjected directly to the heated exhaust.

It is not my intention to limit the invention to the precise details of construction described and shown in the drawings, inasmuch as many of these details are common expedients, and some of my novel combinations may be replaced by other and well-known 115 mechanisms without discarding or materially altering other novel subcombinations.

Having described the invention, what I claim as new, and desire to have protected by Letters Patent, is—

1. In an internal-combustion engine, the combination with a main cylinder having a dome-like cylinder-head the walls of which within said cylinder decline from a substantially central port to the walls of the cylinder, said head comprising a casing forming a supplemental chamber above said dome, and a port establishing communication between said chamber and said cylinder whereby the charge is introduced to said cyl- 130

inder, and the exhaust is discharged therefrom, through said chamber, a loosely-mounted bearing projecting into said chamber, a compression-valve having its stem 5 mounted in said bearing, for said port, a spring acting on said stem and said bearing to normally close said valve, means whereby the exhaust may pass from, and fuel is introduced to, said chamber through an exhaust-port and an intake-port in said chamber, a valve mechanism for each of said ports, and means controlling said valve mechanisms, of a piston moving in said cylinder, and a crank and connecting-rod mechanism.

15 2. In an internal-combustion engine, the combination with a main cylinder having a casing forming a supplemental chamber and an exhaust-chamber, ports respectively establishing communication between said supplemental chamber and said cylinder and said supplemental chamber and said exhaust-chamber whereby the charge is introduced to said cylinder, and the exhaust is discharged therefrom, through said supplemental chamber, a compression-valve for said port into said cylinder, a bearing projected into said exhaust-chamber, a valve mounted in said bearing and movable in said exhaust-chamber, a spring normally closing 20 said valve whereby the exhaust will automatically open said valve, a perforated casing inclosing the stem of said valve and said spring, a plunger-ring on said stem, means whereby fuel is introduced to said supplemental chamber by means of an intake-port therein, a valve mechanism for said intake-port, and means controlling said valve mechanisms, of a piston moving in said cylinder and a crank and connecting-rod mechanism.

25 3. In an internal-combustion engine, the combination with a main cylinder having a casing forming a supplemental chamber and an exhaust-chamber, ports respectively establishing communication between said supplemental chamber and said cylinder and said supplemental chamber and said exhaust-chamber, whereby the charge is introduced to said cylinder and the exhaust is discharged therefrom, through said supplemental chamber, a compression-valve for said port into said cylinder, a bearing projected into said exhaust-chamber, a valve mounted in said bearing and movable in said exhaust-chamber, a bipart stem for said 30 valve, a spring acting on one of said parts to normally close said valve, means controlling said spring whereby the part of the stem carrying said valve will have slight movement independently of said spring, whereby the exhaust will automatically open said valve, means whereby fuel is introduced to said supplemental chamber by means of an intake-port therein, a valve mechanism for said intake-port, and means controlling said valve mechanisms, of a piston moving in said cylinder and a crank and connecting-rod mechanism.

35 4. In an internal-combustion engine, the combination with a main cylinder having a dome-shaped cylinder-head, the walls of which within said cylinder decline from a substantially central port to the walls of the cylinder, said head comprising a casing forming a supplemental chamber, a vapor-chamber and an exhaust-chamber above said dome, and having ports establishing communication between said supplemental chamber and said cylinder, and between said supplemental chamber and said vapor-chamber, and said exhaust-chamber respectively, whereby the charge is introduced to said cylinder, and the exhaust is discharged therefrom through said chamber, a loosely-mounted bearing projecting into said supplemental chamber, a compression-valve having its stem mounted 40 in said bearing, for said port, a spring acting on said stem and said bearing to normally close said valve, a bearing projecting into said exhaust-chamber, a valve mounted in said bearing closing the port establishing communication between said supplemental chamber and said exhaust-chamber, and movable in said last-mentioned chamber, a bipart stem for said valve, a spring acting on one of said parts tending to normally close said valve, means controlling said spring whereby the part of the stem carrying the valve will have slight movement inde-

55 valve mechanisms, of a piston moving in said cylinder and a crank and connecting-rod mechanism.

4. In an internal-combustion engine, the combination with a main cylinder having a casing forming a supplemental chamber and an exhaust-chamber, ports respectively establishing communication between said supplemental chamber and said cylinder, and said supplemental chamber and said exhaust-chamber whereby the charge is introduced to said cylinder, and the exhaust is discharged therefrom, through said supplemental chamber, a compression-valve for said port into said chamber, a bearing projecting into said exhaust-chamber, a valve mounted in said bearing and movable in said exhaust-chamber, a bipart stem for said valve, a spring acting on one of said parts to normally close said valve, means controlling said spring whereby the part of the stem carrying said valve will have slight movement independently of said spring, whereby the exhaust will automatically open said valve, a perforated casing inclosing the stem of said valve and said spring, a plunger-ring on said stem, means whereby fuel is introduced to said supplemental chamber by means of an intake-port therein, a valve mechanism for said intake-port, and means controlling said valve mechanisms, of a piston moving in said cylinder and a crank and connecting-rod mechanism.

5. In an internal-combustion engine, the combination with a main cylinder having a dome-shaped cylinder-head, the walls of which within said cylinder decline from a substantially central port to the walls of the cylinder, said head comprising a casing forming a supplemental chamber, a vapor-chamber and an exhaust-chamber above said dome, and having ports establishing communication between said supplemental chamber and said cylinder, and between said supplemental chamber and said vapor-chamber, and said exhaust-chamber respectively, whereby the charge is introduced to said cylinder, and the exhaust is discharged therefrom through said chamber, a loosely-mounted bearing projecting into said supplemental chamber, a compression-valve having its stem mounted in said bearing, for said port, a spring acting on said stem and said bearing to normally close said valve, a bearing projecting into said exhaust-chamber, a valve mounted in said bearing closing the port establishing communication between said supplemental chamber and said exhaust-chamber, and movable in said last-mentioned chamber, a bipart stem for said valve, a spring acting on one of said parts tending to normally close said valve, means controlling said spring whereby the part of the stem carrying the valve will have slight movement inde-

pendently of said spring, whereby the exhaust will automatically open said valve, a perforated casing inclosing the stem of said valve, and said spring, a plunger-ring on said 5 stem, a bearing projecting into said vapor-chamber, a valve mounted in said bearing and movable in said supplemental chamber and a spring normally closing said valve whereby the piston suction will automatically 10 open said valve, of a piston moving in said

cylinder and a crank and connecting-rod mechanism.

In witness whereof I have hereunto affixed my signature, this 10th day of April, 1905, in the presence of two witnesses.

WILLIAM DIETER.
